UNITED STATES PATENT OFFICE.

GEORGE R. DEMPSTER, OF KNOXVILLE, TENNESSEE.

POWER SHOVEL AND DREDGE.

Application filed January 20, 1922. Serial No. 530,627.

To all whom it may concern:

Be it known that I, GEORGE R. DEMPSTER, a citizen of the United States, residing at Knoxville, in the county of Knox and State 5 of Tennessee, have invented a new and useful Improvement in Power Shovels and Dredges, of which the following is a specification, reference being had to the accompanying drawing.

10 My improvement relates particularly to such power actuated shovels and dredges as embody a boom and a dipper and a stem or stick which is applied to the boom to adapt it for hinge movement whereby the 15 dipper is raised and lowered and also adapt it for endwise movement whereby the dipper is moved toward and from the boom, and the dipper having a hinged bottom door which is held in the closed position by a 20 latch which is to be released by drawing a rope or cable after the dipper has taken its load and has been swung into position for discharging its load.

Formerly the rope or cable used for releasing the latch was drawn manually. The 25 object of my invention is to provide an improved mechanism including a motor for drawing such cable for the release of the latch. Such power shovels and dredges have 30 been made larger and larger, from time to time, in order that the dippers may take larger loads. Thus the latch mechanism has become larger and its engagement made stronger, and consequently a larger force is 35 needed to disengage the latch mechanism, so large as to make it difficult to release the latches by hand power. Yet it is essential that the latch be released promptly and reliably and immediately upon the arrival of 40 the dipper in the discharging position. Hence effort is being made to produce a satisfactory power mechanism for releasing these latches.

In the accompanying drawings,

45 Fig. 1 is an elevation of the boom, dipper, dipper stick and associated parts of a steam shovel of the ordinary type in which the dipper has a hinged bottom controlled by a latch;

50 Fig. 2 is a side elevation of my motor and drum structure;

Fig. 3 is an upright section of the motor and drum structure;

Fig. 3^a is an enlarged fragmentary trans-

verse section through the upper part of the 55 transmission ring;

Fig. 4 is a section on the line, 4—4, of Fig. 3, looking toward the left;

Fig. 5 is an upright section on the line, 5—5, of Fig. 3, looking toward the left; 60

Fig. 6 is an upright section on the line, 6—6, of Fig. 3, looking toward the left;

Fig. 7 is an upright section on the line, 7—7, of Fig. 3, looking toward the left;

Fig. 8 is a detail section showing the attachment of the latch cable to the drum.

Referring to said drawings, A is the boom of an ordinary steam shovel. A¹ is the dipper stem or stick. A² is the dipper supported at the outer end of the dipper stick. 70 A³ is the dipper door hinged to the dipper in the usual manner. A⁴ is a member of a dipper door latch of any ordinary form for controlling said door. A cable, A⁵, engages the dipper from the upper end of 75 the boom for raising and lowering the dipper and the outer end of the dipper stick.

Shipper mechanism, B, is mounted on the boom for shifting the dipper stick, A¹, endwise to shift the dipper toward and from 80 the boom. This mechanism may be of any ordinary form used for this purpose. It comprises a main horizontal shipper shaft, B¹, on which is a spur gear wheel (not shown) meshing with a gear rack on the 85 dipper stick. In my improved apparatus, in the form shown by the drawings, a combined motor and drum structure are applied rigidly to one end of the shipper shaft, B¹, 90 so that said structure must rotate simultaneously with the shipper shaft when the latter rotates.

C is the shaft of the motor and drum structure. One end, C¹, of said shaft is 95 screw-threaded and is seated in the interiorly screw-threaded end of the shipper shaft, B¹, said two shafts being thus immovably joined to each other, so that the shaft, C, is rotated whenever the shaft, B¹, 100 is rotated for shifting the dipper stick, A¹, endwise in either direction. The purpose of such rotation of the shaft, C, is to cause the rotation of the drum whenever the dipper stick is shifted endwise, as will be described further on.

D is the drum. This loosely surrounds the shaft, C, and has flanges, D¹. Between the flanges it has a spiral groove, D², to receive

a latch rope or cable, D⁸, being wound on the drum. At the left of the drum the shaft, C, is screw-threaded and receives a nut, C², to prevent the drum from moving leftward.

5 Rightward movement of the drum is prevented by the piston structure. Said structure has a hub, E¹, surrounding the shaft, C, and held against movement thereon by a tongue or key, E², and a set-bolt, E³. From said hub a piston arm, E⁴, extends radially outward near and parallel to the adjacent end of the drum. At its outer end said arm supports a piston stem, E⁵, which is concentric to the shaft, C. At its end opposite the arm, E⁴, the piston stem terminates in a piston head, E⁶, the right hand face of which rests against the adjacent face of the adjacent drum flange, D¹. During the relative rotations of the drum and the piston, said piston head slides on said face of said drum flange. The hub, arm, stem and piston head are shown as a single casting. A collar, E⁷, is threaded around the outer or right hand end of the hub, E¹, of the piston structure, said collar being fitted to be held immovably on the hub. At the left hand part of said collar is a circumferential channel, E⁸, which receives one member, F, of a steam admission ring. Said member, F, is 30 flattened in a plane to which the shaft, C, is perpendicular, and said member is even with the left hand face of the collar, E⁷. A channel, E⁹, corresponding in reverse to the channel, E⁸, is formed on the hub, E¹, near the arm, E⁴, of the piston structure. In said channel is seated the second member, F¹, of the steam admission ring. Said member extends radially outward from said channel and is then flanged rightward to meet the 40 outer part of the adjacent radial face of the ring member, F. Cap screws, F², extend through the member, F, into the member, F¹, to immovably bind said members to each other. The seating of said members in the 45 channels, E⁸ and E⁹, is to be sufficiently loose to permit easy turning of the piston structure hub in said ring, and yet the joint between said ring and said hub should be made as close as is permissible, in order that the 50 escape of steam along said joints may be brought to a minimum. Adjacent the left hand face of the member, F, an annular seat, F³ is formed for a packing ring, F⁴, which extends over the joint between the member, F and the hub, E¹. At the left of the inner 55 part of the member, F¹, a similar annular seat F⁵ is formed on said hub. A packing ring, F⁶, rests on said seat and extends across the joint between the member, F¹, and the hub. On the opposing faces of said packing rings 60 and opposite each other are lugs F⁷ which enter the ends of expanding coiled spring, F⁸, which serves to press said rings sidewise against the adjacent members of the admission ring and the adjacent faces of the

hub. The function of said packing rings is to further limit the escape of steam through the joints between the admission ring and the hub.

For the admission of steam to the admission ring, a port, F⁹, is formed in the flange of the ring member, F¹. Said port is radial to the shaft, C, and is interiorly screw-threaded to receive the exteriorly screw-threaded steam delivery pipe, F¹⁰. Said pipe is to lead from a source of steam supply and is to be suitably secured against movement, whereby the admission ring is also held against movement. Hence said ring does not rotate during the rotations of the shaft, C, and the piston structure.

The steam port, F⁹, opens into the annular passage, F¹¹, formed between the flange of the ring member, F¹, and the packing rings, F⁴ and F⁶ (Figs. 3, 3^a and 6). A steam passage, F¹², extends from the passage, F¹¹, through the piston arm, E⁴, and through the piston stem, E⁵ and through the piston arm, E⁴, and through the piston head, E⁶.

Thus, regardless of the rotation of the piston structure (while as above stated, the admission ring and steam delivery pipe are stationary), there is communication between the steam passage in the piston stem and the steam passage in the admission ring. Thus it will be seen that there is at all times a continuous steam passage from the steam delivery pipe through the admission ring and the piston structure hub and the piston arm and the piston stem and the piston head, the discharge being through the free end of said head.

The piston head and the piston stem enter a "cylinder" having two walls, G¹, and one will, G². The wall, G², is in a plane to which the shaft, C, is perpendicular. The walls, G¹, are concentric to said shaft and their left hand edges bear against the adjacent face of the adjacent drum flange, D¹. Cap screws, G³, extend from the right through the walls, G¹, into said drum flange, whereby said walls are firmly bound to said flange. The walls, G¹ and G², and said drum flange form a chamber which is rectangular in cross section and concentric to the shaft, C; and said chamber is of the same cross section as the piston head, E⁶, and is at the same distance from the axis of the shaft, C. Hence said chamber is adapted to receive the piston head and piston stem and permit the sliding of said head in said chamber. The end of said chamber which is adjacent the piston arm, E⁴, is open. The other end of said chamber is closed by an end wall, G⁴, which is transverse to the walls, G¹ and G², and approximately radial to the shaft, C.

It will now be seen that if steam is admitted through the steam delivery pipe, F¹⁰, the steam will follow the passages above

described and discharge from the piston head into the closed end of the cylinder chamber and force the cylinder into movement away from the piston head, it being remembered that the entire piston structure is fixed on the shaft, C, and the drum, on which the cylinder is supported, being loose and free to rotate on said shaft. It will also be seen that the action of the steam for the turning of the cylinder and drum is limited to one direction and to only a part of one rotation of the drum. Hence the steam motor which is thus combined with the drum is adapted to draw the latch cable through only a short distance, the distance required for releasing the latch.

The latch cable, D³, extends from the drum to the movable latch member, A⁴, and said cable may be secured to the drum in any desired manner. The drawings show it extending through the aperture, D⁴, in the right hand drum flange and thence under a clamping plate, D⁵, which is secured to said flange by a bolt, D⁶.

To limit the turning of the drum relative to the piston structure, a stop, H, is seated on the outer face of the right hand drum flange, D¹, in position to meet the piston arm, E⁴, and in position to be arrested by said arm when the piston head is in the open end of the cylinder. To reduce shock when said stop meets said arm, a socket is formed in the stop to open toward said arm, and a coiled spring, H¹, is seated in said socket and made to project therefrom toward the piston arm to make impact therewith.

For the control of steam in the delivery pipe, F¹⁰, a three-way valve, F¹³, (Fig. 1) is placed on said pipe to serve for admitting steam into the admission ring and also to cut off such admission and allow exhaust from said ring, whereby the drum may reverse until the forward end of the piston head meets the end wall, G⁴, of the cylinder. In practice it has been found that the force exerted on the latch cable, D³, while the door is swinging into the closed position is sufficient to cause said cable to thus reverse the drum through the necessary fractional turn.

The foregoing description of the operation of my apparatus relates only to the action of the motor, that action being limited to the turning of the drum only as far as is needed in connection with the releasing and reengaging of the latch.

When the dipper stick, A¹, is being shifted endwise on the boom by the turning of the shipper mechanism shaft, B¹, the shaft, C, and all the mechanism supported thereby are correspondingly rotated for winding the latch cable on or unwinding it from the drum in harmony with the movement of the dipper toward or away from the shafts, B¹ and C, whereby the length of said cable be-

tween the latch and the drum is substantially maintained, in order that at any time the partial rotation given by the motor to the drum will draw the latch cable for the release of the latch.

When there is no steam in the cylinder and the entire structure is being turned, the drum may be turned independently of the shaft, C, as far as the piston permits. But such turning of the drum is only fractional and does not interfere with the winding and unwinding of the drum during the rotation of the entire structure by the rotation of the shipper shaft, B¹.

I claim as my invention,

1. In an apparatus of the kind described, the combination with a dipper-supporting structure comprising a boom and a dipper stick shiftable endwise on said boom, and a dipper supported on said stick and comprising a closing member to be released for discharging the load, and rotary means for shifting the dipper stick endwise on the boom, of a cable having one end in operative relation with said closing member, means concentric with the axis of said shifting means for taking up and paying out said cable approximately synchronously with the endwise movements of the dipper stick, and an operator-controlled motor concentric with said axis for pulling said cable for actuating said closing member, substantially as described.

2. In an apparatus of the kind described, the combination with a dipper stick, means for shifting the dipper stick endwise, and a dipper supported on the dipper stick and comprising a closing member to be released for discharging the dipper load, of a drum and drum structure shaft rotatable approximately synchronously with the endwise movements of the dipper stick, a fluid motor cylinder concentric with the drum axis and fixed to the drum, a piston concentric with and fixed on said shaft for partially turning said drum independently of said synchronous rotation of the drum, and a cable having one end in operative relation with said closing member and having its other end attached to said drum, substantially as described.

3. In an apparatus of the kind described, the combination with a dipper stick, means for shifting the dipper stick endwise, and a dipper supported on the dipper stick and comprising a closing member to be released for discharging the dipper load, of a drum operatively connected with the dipper stick shifting means for rotation approximately synchronously with the endwise movements of the dipper stick, a hollow piston motor concentric with the drum axis for partially turning said drum independently of said synchronous rotation of the drum, and a cable having one end in operative relation

with said closing member and having its other end attached to said drum, substantially as described.

4. In an apparatus of the kind described, the combination with a dipper stick, means for shifting the dipper stick endwise, and a dipper supported on the dipper stick and comprising a closing member to be released for discharging the dipper load, of a drum

10 supported by said shifting means for rotation approximately synchronously with the endwise movements of the dipper stick, a motor concentric with the drum axis for partially turning said drum independently.

15 of said synchronous rotation of the drum, and a cable having one end in operative relation with said closing member and having its other end attached to said drum, substantially as described.

20 5. In an apparatus of the kind described, the combination with a dipper stick and means comprising a shaft for shifting the dipper stick endwise, and a dipper supported on the dipper stick and comprising a
25 closing member to be released for striking

25 closing member to be released for discharging the dipper load, of a drum supported by said shaft for rotation approximately synchronously with the endwise movements of the dipper stick, a motor having one mem-

30 member fixed on the drum and having the other member fixed on said shaft for partially turning said drum independently of said synchronous rotation of the drum, and a cable having one end in operative relation
35 with said closing member and having its other end attached to said drum, substantially as described.

6. In an apparatus of the kind described, the combination with a dipper stick, means for shifting the dipper stick endwise, and a dipper supported on the dipper stick and comprising a closing member to be released for discharging the dipper load, of a rotary structure comprising a drum and motor, the motor comprising a piston structure hub and a stationary admission ring surrounding said hub, and the drum and motor, excepting the admission ring, being rotatable approximately synchronously with the end

50 approximately synchronously with the end-
wise movements of the dipper stick, the motor
serving for partially turning said drum
independently of said synchronous rotation
of the drum, and a cable having one end in
operative relation with said closing mem-
55 ber and having its other end attached to
said drum, substantially as described.

60 7. In an apparatus of the kind described, the combination with a dipper stick, means for shifting the dipper stick endwise, and a dipper supported on the dipper stick and comprising a closing member to be released for discharging the dipper load, of a rotary structure comprising a drum and an oscillating motor concentric with the drum axis and comprising a stationary admission ring, and

the drum and the motor, excepting the admission ring, being together rotatable approximately synchronously with the endwise movements of the dipper stick, the motor serving for partially turning said 70 drum independently of said synchronous rotation of the drum, and a cable having one end in operative relation with said closing member and having its other end attached to said drum, substantially as described. 75

8. In an apparatus of the kind described, the combination with a dipper stick a shaft, means on said shaft for shifting the dipper stick endwise, and a dipper supported on the dipper stick and comprising a closing member to be released for discharging the dipper load, of a drum supported by said shifting means for rotation approximately synchronously with the endwise movements of the dipper stick, a motor comprising a piston fixed on said shaft and a cylinder forming a part of the drum structure, the latter being on the drum and the function of which motor is to partially turn said drum independently of said synchronous rotation of the drum, and a cable having one end in operative relation with said closing member and having its other end attached to said drum, substantially as described. 80 85 90

9. In an apparatus of the kind described, 95
the combination with a dipper stick, means
for shifting the dipper stick endwise, and a
dipper supported on the dipper stick and
comprising a closing member to be released
for discharging the dipper load, of a drum
supported by said shifting means for rotation
approximately synchronously with the endwise movements of the dipper stick, 100
a motor comprising a piston and a cylinder
which is on the drum and one wall of which
is formed by the end of the drum and the
function of which motor is to partially
turn said drum independently of said synchronous 105
rotation of the drum, and a cable having one end in operative relation with
said closing member and having its other end attached to said drum, substantially as
described. 110

10. In an apparatus of the kind described, the combination with a dipper stick, means for shifting the dipper stick endwise, and a dipper supported on the dipper stick and comprising a closing member to be released for discharging the dipper load, of a drum supported by said shifting means for rotation approximately synchronously with the endwise movements of the dipper stick, a motor comprising a cylinder concentric with the axis of the drum and a curved piston extending into said cylinder and having a passage opening through the inner end of the piston, the function of said motor being to partially turn said drum independently of said synchronous rotation of the drum, and a cable having one end in operative re- 115 120 125 130

lation with said closing member and having its other end attached to said drum, substantially as described.

11. In an apparatus of the kind described, 5 the combination with a dipper stick, means, including a rotary shaft, for shifting the dipper stick end wise, and a dipper supported on the dipper stick and comprising a closing member to be released for discharging 10 the dipper load, of a drum loose on said shaft, a cylinder on the drum, a piston rigid

on said shaft and extending into said cylinder, means for limiting the relative movement of the drum and the piston, and a cable having one end in operative relation with 15 said closing member and having its other end attached to said drum, substantially as described.

In testimony whereof I have signed my name, this 31st day of December, in the year 20 one thousand nine hundred and twenty-one.

GEORGE R. DEMPSTER.
